UNITED STATES PATENT OFFICE.

CHARLES H. DIENER, OF PHILADELPHIA, PENNSYLVANIA.

CARBURETER.

1,156,836.

Specification of Letters Patent. Patented Oct. 12, 1915.

Application filed October 7, 1914. Serial No. 865,530.

To all whom it may concern:

Be it known that I, CHARLES H. DIENER, a citizen of the United States, residing at Philadelphia, in the county of Philadelphia and State of Pennsylvania, have invented certain new and useful Improvements in Carbureters, of which the following is a specification, reference being had to the accompanying drawings.

10 This invention relates to improvements in carbureters, and has for its primary object to provide a device of this character adapted to be arranged in the exhaust pipe of an engine for heating kerosene and other comparatively heavy oils, whereby the expense incident to the operation of the engine may be reduced to a minimum.

The invention has for a more particular object to provide an improved construction 20 of the heater body, and means for securing the same in the exhaust pipe, a carbureter proper in communication with the gas passage of the heater, and oil and water supply pipes in communication with the carbureting chamber and extending through the heater body whereby the same are heated by the exhaust gases from the engine.

The invention has for another and very important object to provide an improved 30 construction of the carbureter proper, the same embodying a gasoline reservoir to contain the initial fuel supply, means for mounting said carbureter upon the exhaust pipe and directing heated air into the carbureting chamber, a mixing valve opened by suction upon the intake stroke of the engine piston whereby the air is drawn into the carbureting chamber, oil and water supply pipes, and a control valve for regulating 40 the supply of oil and water through the carbureting chamber.

The invention has for still another object to generally improve and simplify the construction of devices of the above character, 45 to increase their efficiency and reliability in operation, and enable the same to be produced at comparatively small manufacturing cost.

With the above and other objects in view 50 as will become apparent as the description proceeds, the invention consists in certain constructions, combinations, and arrangements of the parts that I shall hereinafter fully describe and claim.

55 For a full understanding of the invention, reference is to be had to the following

description and accompanying drawings, in which—

Figure 1 is a vertical section through the carbureter showing the same connected in 60 the exhaust pipe of a gas engine; Fig. 2 is a section taken on the line 2—2 of Fig. 1; Fig. 3 is a section taken on the line 3—3 of Fig. 1; Fig. 4 is a section taken on the line 4—4 of Fig. 3; Fig. 5 is a section taken 65 on the line 5—5 of Fig. 1; Fig. 6 is a section taken on the line 6—6 of Fig. 5; Fig. 7 is a top plan view of the mixing chamber; Fig. 8 is a face view of the head of one of the needle valves.

Referring in detail to the drawings 5 and 6 designate two sections of the exhaust pipe of a gas engine which extend at right angles with respect to each other. One end of the horizontal section 6 of this pipe is threaded 75 for the connection thereto of an elbow joint member 7. This member is formed upon its upper open end with a substantially annular outwardly projecting flange 8, thereby forming the upstanding annular shoulder 9. 80

The body of the heater or mixer indicated at 10, includes an elongated intermediate portion 11, the opposed end walls of which are integrally connected by a tube 12. Below this tube the body 10 is contracted and 85 formed with a circular outlet 13 for the exhaust gases. The edge of this outlet is adapted to seat upon the annular flange 8 of the elbow joint member 7. The tube 12 is centrally formed with a depending inferiorly threaded boss 14 in which the upper threaded end of a bolt 15 is adapted to be engaged. This bolt is inserted upwardly through an opening provided in the bottom wall of the elbow 7, as clearly shown in Fig. 95 1. It will thus be apparent that by turning the bolt 15, the body 10 may be drawn downwardly into tight engagement upon the upper end of the elbow and thereby rigidly secured in place. The body 10 is also provided with an upwardly extending reduced cylindrical portion 16, the upper end of which is provided with exterior screw threads.

17 indicates a connecting nipple, whereby 105 the upper end of the body may be connected to the section 5 of the exhaust pipe. This nipple includes a polygonal shaped body portion having an outwardly projecting annular flange 18 formed upon one end. This 110 flange is adapted for engagement against the end of the upwardly extending portion 16

of the body 10 and at the inner edge of said flange or annular shoulder 19 is formed to fit within this reduced end 16 of the body. A coupling nut 20 is interiorly threaded as at 21 for engagement with the exterior threads on the body 10, and is formed upon one of its ends with an inwardly projecting annular flange 22, adapted for engagement over and upon the flange 18 on the connecting nipple 17. By threading this nut inwardly upon the upper end 16 of the body it will be apparent that the connecting member 17 is securely held in connection therewith. The body of the nipple 17 is also formed with a reduced exteriorly threaded extension 23 for engagement with the threads formed upon the section 5 of the exhaust pipe. In this manner it will be observed that the body 10 may be very easily 15 and quickly arranged in the exhaust pipe of the engine. In cases where the exhaust pipe is not provided with an elbow joint member, it will, of course, be necessary to resort to some slight modifications in the connecting or 20 attaching means for the body. As such changes will be obvious to the skilled mechanic, it will be understood that I do not desire to be limited to the precise details of construction above set forth.

20 The body 10 is interiorly formed above the tube 12 with the spaced converging walls 24 which produce a gas passage 25. The opposite ends of this passage are open, one of said ends being interiorly threaded for the 25 connection of the intake pipe 26 thereto, the other end of said pipe being suitably connected to the engine cylinder. The outer converging walls 24 terminate at their point of juncture with each other slightly below 30 the upper edge of the reduced portion 16 of the body so as to permit of the free passage of the flame and exhaust gases downwardly around the walls 24 and between the same and the outer wall of the body. This exhaust passage through the body, designated by the numeral 27, also extends round the tube 12, the gases being finally exhausted therefrom through the outlet end 13 of the body and into the nipple 7.

30 The carbureter proper, shown at 28, includes a cylindrical body in which is provided a gasoline reservoir 29. An interior cylindrical wall 30 constitutes the outer wall of the mixing chamber proper, and is formed 35 with a lateral extension 31 which provides a passage 32 affording communication between the mixing chamber and one end of the gas passage 25 in the body 10. This extension 31 is provided with ears or flanges adapted to be secured by means of suitable bolts 33 to the end of the body. The body of the carbureter is also formed with a depending annular boss or extension 34 which is adapted to be fitted within the split collar 35 formed upon the intermediate portion 40 of a saddle plate 36. This saddle plate is of semicircular form in cross section and is provided upon its inner face with two series of ribs 37 which extend transversely and inwardly from the opposite longitudinal edges 70 of said plate. The split collar 35 is formed at its opposed edges with the laterally projecting ears 38, each having an opening therein. One of these openings is threaded to receive a threaded clamping screw 39. By the adjustment of this screw, it will be understood that the split collar may be drawn together and tightly clamped upon the wall of the boss or extension 34 on the carbureter body.

40 At the upper end of the extension 34 the internal valve seat 40 is formed, upon which the valve disk 41 is normally and yieldingly held by a spring 42. This spring is arranged around the valve stem 43 and also receives 45 within its upper end the reduced portion 45 of a cylindrical extension 44 formed upon the head or cap plate 46. A shoulder 47 is thus produced against which the upper end of the coil spring 42 bears. The head 46 includes a threaded portion 48 for engagement with the interior threads formed upon the upper end of the interior wall 30 of the carbureting chamber. The extension 44 is formed with a longitudinal bore 49 in which the valve stem 43 loosely fits. The head or cap member 46 is also provided with an enlarged circular disk 50 which extends over and closes the upper end of the gasoline reservoir 29. Upon the hexagonal body 51 100 of the head 46 a suitable wrench may be applied in order to conveniently thread the extension 48 thereof into the upper end of the mixing chamber or remove the same. Through the closure head a series of spaced 105 openings 52 are formed which communicate with the carbureting chamber. Upon the head 46 a circular valve plate 53 is arranged which is also provided with a series of openings 54. This valve plate is formed with a 110 central relatively large opening 55 through which the shank of a bolt 56 extends. This bolt is threaded for engagement in the threaded socket or recess indicated at 57 which is centrally formed in the head 46. Upon the bolt between the head thereof and the valve plate 53 a washer or bushing 58 is disposed.

55 59 designates a leaf spring also having a central opening 60 to receive said bolt, said spring being disposed between the head of the bolt and the bushing 58. One extremity of this leaf spring is reduced and angularly bent as at 61 for engagement in a notch or recess 62 formed in the periphery of the valve plate 53. The other end of said spring is formed with a finger ring or loop 63. It will be apparent from this construction that the adjustable valve plate 53 provides means for regulating the supplementary supply of 115

air to the carbureting chamber, the primary supply for which is provided at the lower end of said chamber through the medium of the spaced ribs 37 upon the saddle plate. 5 The leaf spring serves to retain the adjustable valve plate against casual movement with respect to the closure head and thereby maintain the openings in said plate in proper position with relation to the openings 52 in the closure head. The mixing chamber 28 is provided at its lower end at diametrically opposite points with the outwardly projecting interiorly and exteriorly threaded nipples 64. A similar nipple is 10 also formed upon the wall of the carbureter body at the lower end of the gasoline reservoir 29 and extends at right angles to the first named nipples. At each of these points, the body of the carbureter is formed 15 with a passage or orifice 65 which communicates at its outer end with the bore of the nipple. The inner end of the orifice is reduced in diameter, as indicated at 66, to receive the needle point 68 of an adjustable 20 valve rod 69. This rod is threaded, as at 70, for engagement with the interior threads upon the nipple 64. The outer end of said rod is formed with a knurled head 71. A nut 72 is also threaded upon the nipple and 25 secures one end of a leaf spring 73 tightly against the wall of a carbureter 28. The free end of the spring bears upon the periphery of the knurled head 71. The end edge of the 30 nipple 64 is dished or concaved to receive a packing gland 74. A gland nut 75 is threaded upon the outer end of the nipple to tightly 35 compress the packing 74 around the valve rod and against the end face of the nipple. An opening 76 in the bottom wall of the gasoline 40 reservoir 29 affords communication between the same and one of the orifices 65. The reduced inner portion 66 of each orifice opens upon the valve seat 40.

The lower end of the body of the carbureter, at one side of the mixing valve and below the lateral extension 31 is formed 45 with a transversely extending longitudinally tapering valve bore 77. With one side of this valve bore and adjacent the opposite ends 50 thereof the obliquely extending passages 78 communicate, the respective passages connecting said bore with the diametrically opposed supply orifices 65.

79 designates a rotary valve member which 55 is arranged within the bore 77 and tapers in conformity thereto. This valve member, however, is of greater length than the bore and at its smaller end is provided with the cylindrical extension 80 terminating in a reduced threaded stud 81. At opposite sides of the center of the valve member 79, the same is formed with angularly disposed oppositely extending openings or ports 82. These ports are adapted to connect the respective passages 78 in the body of the mixer 60

with the inner ends of the openings 83 which are formed in a lateral extension of the carbureter body. The outer ends of these openings are threaded, to which the oil and water pipes, indicated at 84 and 85 respectively are detachably connected. A nut 86 is threaded upon the reduced end 81 of the valve member 79 and between said nut and the wall of the mixer a coil spring 87 is arranged upon the cylindrical extension 80 of the valve member. This spring acts to yieldingly hold the valve member against longitudinal shifting movement in the bore 77 so that the ports 82 are properly disposed for registration with the passages 78 and openings 83 when said valve member is rotated. The opposite end of the valve member is formed with a suitable finger piece 88 whereby the same may be conveniently turned to the desired position. The end face of each 65 of the heads 71 on the valve rod 69 are provided with a circularly arranged series of numerals, from 0 to 9, whereby the approximate quantity of fluid flowing through each of the orifices 65 to the carbureting 70 chamber may be ascertained by the operator. The valve rods are rotated until the desired numeral thereon is disposed immediately below the free end of the leaf spring 73. 75

The disk 50 of the closure head 46 is preferably provided with a threaded opening 89 located above the open end of the gasoline reservoir 29. In this opening the neck of a filling funnel 90 is removably threaded. A suitable cap or cover plate 91 is hingedly 80 mounted as at 92 upon the upper end of the funnel. By means of this filling funnel attachment, the gasoline reservoir may be conveniently filled. 85

Having now described the construction 105 and arrangement of the several parts of my improved carbureter, its operation will be understood as follows: The reservoir 29 having been supplied with gasoline and the pipes 84 and 85 connected to a kerosene tank and a water tank respectively, the valve 79 is first completely closed. The valve rod 69 controlling the supply of gasoline is then turned until the numeral 6 or 7 on the head of the valve is below the spring 73, thus indicating that the valve is about three-fourths open. After the engine has been started on the gasoline as the operating fuel, the valve 110 69 controlling the kerosene supply is opened until the indicating numeral 7 is at the 115 upper side of the valve head and the water control valve is also opened until the numeral 4 or 5 is uppermost. After the lapse of a short time or until the body 10 is fairly hot, the valve 79 is turned to its open position so as to admit both the water and kerosene oil through the ports 82 and passages 78 to the orifices 65 at opposite sides of the carbureting chamber. The supply of gasoline 120 is now reduced and the engine run on this 125 130

reduced gasoline supply until the same is entirely exhausted. The exhaustion of this gasoline supply requires only about eight or ten minutes after which the engine will operate entirely upon the kerosene oil as a fuel. It will be understood that in the intake stroke of the engine piston, the valve 41 is drawn open by suction and the heated air drawn upwardly between the ribs 37 of the saddle plate over the hot exhaust pipe and into the mixing chamber proper. As this air passes into the mixing chamber, the oil and kerosene entering through the orifices 65 mixes therewith and the whole is then drawn into the gas passage 25 of the body 10. The flame and products of combustion from the engine exhaust striking upon the walls of this gas passage heat the same to a very high temperature so that the kerosene oil will be completely vaporized. This oil and the water, it will be understood, is initially heated in its passage through the pipes 84 and 85 as said pipes extend through the tube 12, which is itself highly heated by the passage of the exhaust gases around the same. Thus, the complete vaporization of the kerosene oil in its passage through the carbureter body is assured and it is finally drawn through the intake pipe 26 and into the explosion chamber of the engine cylinder, in proper condition for combustion. The auxiliary air supply valve at the top of the mixer body is completely closed when the engine is started. This additional air supply is only necessary when the engine is operating under a heavy load.

From the foregoing description taken, in connection with the accompanying drawings, the construction, manner of operation, and several advantages of my invention will be obvious.

My improved carbureter provides a simple and efficient means for utilizing kerosene and other comparatively heavy oils as fuel in the operation of gas engines. The operating expense may therefore be appreciably reduced, and without diminution of power. By providing a gas passage through the carbureter body of the particular form illustrated in the drawings, the mixture of air, oil, or water is held in contact with the heated walls of said passages for a maximum length of time so that the complete vaporization of the oil is assured. My improved carbureter may also be very easily and quickly arranged in the engine exhaust pipe or removed therefrom and in view of the accessibility of the several operating parts, the device may be repaired and kept in thorough working condition with but little expense or manual labor.

The carbureter may, of course, be constructed in various sizes and also in other forms than I have indicated in the accompanying drawings in order to meet various

circumstances or conditions which may arise in connection with the use thereof. The several coöperating parts of the mechanism may also be modified in many minor respects and I therefore reserve the privilege of resorting to all such legitimate alterations in the form, proportion, and arrangement of the several elements as may be fairly embodied within the spirit and scope of the invention as claimed.

What I claim is:

1. In a carbureter, the combination with the exhaust pipe of an engine, of a body provided with an exhaust receiving chamber and a gas passage extending through said body and opening upon the opposite sides thereof, a carbureter proper mounted upon the exhaust pipe and having a valve opened by suction whereby air is drawn into the carbureting chamber over the exhaust pipe, said carbureting chamber being connected to one end of the gas passage, fuel and water supply pipes extending through the exhaust receiving chamber of said body, and a single valve to uniformly control the flow of the fuel and water to the carbureter.

2. In a carbureter, the combination with the exhaust pipe of an engine, of a body connected to the exhaust pipe provided with an exhaust receiving chamber and a gas passage having diverging portions extending through the chamber and opening upon the opposite sides of said body, a carbureter proper mounted upon the exhaust pipe and connected to one end of said gas passage, a valve normally closing communication between the carbureting chamber and the atmosphere adapted to be opened by suction whereby air is drawn into the chamber over the exhaust pipe, said carbureter being provided with a fuel receiving chamber, a valve to control the supply of fuel to the carbureting chamber, fuel and water supply pipes extending through the exhaust chamber of said body, and a single valve to simultaneously and uniformly vary the feed of fuel and water through said pipes to the carbureter.

3. In a carbureter, the combination with the exhaust pipe of an engine, of a body connected to the exhaust pipe and provided with a gas passage having diverging portions opening upon opposite sides of said body, and said body being further provided with a tube below the gas passage, a carbureter proper mounted upon the exhaust pipe and connected to one end of the gas passage, a spring held valve opened by suction whereby air is drawn over the exhaust pipe into the carbureting chamber, an adjustable air valve to provide a constant supply of air to the chamber, fuel and water supply pipes extending through the tube of said body, said carbureter having passages opening upon the valve seat with which the respective pipes are connected, and a single adjustable

valve for simultaneously and uniformly controlling the supply of oil and water to said passages.

4. In a carbureter, a body having an exhaust chamber and a gas passage including diverging portions opening upon the relatively opposite ends of said body, a tube integrally connecting the ends of said body and extending through said exhaust chamber, a carbureter proper in communication with one end of the gas passage, and oil and water supply pipes extending through said tube and connected to the carbureter. 40

5. In a carbureter, a body having an exhaust chamber and a gas passage including diverging portions opening upon the relatively opposite ends of said body, a tube integrally connecting the ends of said body and extending through said exhaust chamber, a carbureter proper in communication with one end of the gas passage, oil and water supply pipes extending through said tube and connected to the carbureting chamber, and a valve for simultaneously and correspondingly varying the supply of oil and water to the carbureting chamber. 50

6. In a carbureter, a body having an exhaust chamber and a gas passage provided with diverging portions opening through the opposite ends of said body, a tube integrally connecting the end walls of said body and extending through said exhaust chamber, a carbureter proper in communication with one end of the gas passage, said carbureter being provided with a reservoir to con- 55

tain an initial fuel supply, a valve to regulate the supply of said fuel to the carbureting chamber, oil and water supply pipes extending through said tube and connected to the carbureting chamber, and a valve mounted in the wall of the carbureting chamber to simultaneously and correspondingly vary the supply of the oil and water to said chamber. 60

7. In a carbureter, the combination with the exhaust pipe of an engine, of a body having an exhaust receiving chamber, means for securing said body to the exhaust pipe, said body also having a gas passage including diverging portions opening upon the opposite ends of said body, a carbureter proper in communication with one end of the gas passage, a mixing valve in said carbureter, means for supporting said carbureter upon the exhaust pipe and directing hot air thereto when the valve is opened, oil and water pipes extending through said body and heated by the passage of the exhaust gases therethrough, said pipes being connected to the carbureter, and a common regulating valve 65 to simultaneously and correspondingly vary the supply of the oil and water to the carbureting chamber. 70

In testimony whereof I hereunto affix my signature in the presence of two witnesses. 65
